UNITED STATES PATENT OFFICE.

CHARLES MARTIN SHAW, OF YOKER, SCOTLAND.

DESIGN FOR AN AUTOMOBILE-BODY.

55,334.

Specification for Design.

Patented May 25, 1920.

Application filed December 30, 1919. Serial No. 348,495. Term of patent 14 years.

To all whom it may concern:

Be it known that I, CHARLES MARTIN SHAW, a subject of the King of Great Britain, residing at Yoker, Scotland, have invented a new, original, and ornamental Design for an Automobile-Body, of which the following is a specification, reference being had to the accompanying drawing, forming part thereof.

On the drawing:

Figure 1 is a side view of an automobile body showing my new design, and

Fig. 2 is a front view thereof.

The body is made of curved formation without sharp angles and has a base portion *a* shaped as shown, the front forming an ornamental aperture *b* for air admission for engine cooling purposes, and an upper portion having outwardly extending parts *c* which form the sides of the seat. An ornamental canopy *d* is also secured to the body by means of standards *e*.

I claim:

The ornamental design for an automobile body, as shown and described.

CHARLES MARTIN SHAW.
